Primary Examiner — Andrew Kerr*Assistant Examiner* — Courtney J Clark-Rasheed(74) Attorney, Agent, or Firm — Lowe Graham Jones PLLC(57) CLAIM

I claim the ornamental design for a container lid, as shown and described.

DESCRIPTION

FIG. 1 is a top front perspective view of a container lid, showing my new design.

FIG. 2 is a front elevational view of the container lid.

FIG. 3 is a rear elevational view of the container lid.

FIG. 4 is a left side elevational view of the container lid.

FIG. 5 is a right side elevational view of the container lid; and,

FIG. 6 is a top plan view of the container lid.

The broken line illustration of a container is for the purpose of illustrating environmental structure which forms no part of the claimed design. Features shown in broken lines form no part of the claimed design.
